UNITED STATES PATENT OFFICE

ROBERT H. LAWSON, OF PAWTUCKET, RHODE ISLAND, ASSIGNOR TO HEMPHILL COMPANY, OF CENTRAL FALLS, RHODE ISLAND, A CORPORATION OF MASSACHUSETTS

THREAD FEEDING MEANS FOR KNITTING MACHINES

Application filed December 18, 1929. Serial No. 414,932.

This invention relates to and supplements the mechanism disclosed in the patent to Lawson et al. 1,702,608, February 19, 1929, and has in view the provision of some means whereby the wrapping floats resulting from the operation of the disc 117 in the Lawson patent above referred to will not be unduly lengthened by the usual high splice and double sole floats. If a high splice mechanism were applied to a mechanism such as that shown in the Lawson patent the wrapping floats of a thread 103 would, of necessity, pass around the high splice floats and, as the said floats ordinarily constitute chords connecting the knit-in portion of the high splice, the wrapping floats of a thread 103 would be unduly lengthened, thus necessitating a subsequent cutting operation to remove the resulting long wrapping floats of a thread or threads 103.

Application Serial No. 379,302, filed July 18, 1929, discloses a means for acting upon the high splice floats so that the floats of the threads corresponding to threads 103 in the Lawson patent will not be unduly lengthened but may pass in a straight line from the last wale where knit in in one course to the first wale where knit in in a succeeding or following course. Whereas in the copending application referred to the means for acting upon the high splice floats consists of a cutter, as disclosed herein means is provided to draw out more of the high splice thread or yarn during each course of knitting of the high splice so that the before mentioned chords connecting the opposite edges of the high splice will be slack thereby permitting a thread corresponding to the thread 103 of the Lawson patent to extend in a substantially straight line at the rear of the knit-in wales from the last wale where knit in in one course to the first knit in wale in a following course of knitting, the slack high splice floats being drawn by the wrapping floats against the rear face of the fabric and between the wrapping floats and the knit-in wales.

In the drawings:

Fig. 1 is a plan view of a latch ring with the improvements applied;

Fig. 2 is a sectional view taken along the

line 2—2, Fig. 1 looking in the direction of the arrow, the wrap stripe mechanism not being shown;

Fig. 3 is a sectional view taken along the line 3—3, Fig. 1 looking in the direction of the arrow, the needles and thread being omitted;

Fig. 4 is a sectional view taken along the line 4—4, Fig. 1 looking in the direction of the arrow; and

Figs. 5, 6, 7, 8 and 9 illustrate diagrammatically the knitting of a partially reinforced course while wrapping an additional thread around certain, selected needles.

A latch ring 1 has the usual bracket arms 2 through which a pivot pin 3 extends and pivotally carried by the said pivot pin 3 in the usual manner are yarn levers 4, 5, 6, 7, and 8. The yarn lever 4 is the so-called high splice lever which, during the knitting of the high splice, is adapted to feed a thread T to one half, more or less, of the needles during the knitting of each course, the thread T floating from the last knit-in wale of one course to the first knit-in wale of the following course. The yarn levers 5, 6, 7, and 8 carry the threads for knitting the body of the stocking, the heel and toe, as well as plating and interchangeable striping threads.

At 9 is shown a disc corresponding to the disc shown at 117 in the Lawson patent and carrying porcelain eyes 10. The number of such porcelain eyes as well as their relative disposition upon the periphery of the disc 9 is not important as they may be arranged to suit the particular pattern or design to be knit-in by the plating threads that are fed to and wrapped around certain needles by the eyes 10 and in a manner similar to or identical with that disclosed in the Lawson patent.

The usual thread or yarn binder 11 is shown attached at 12 to an extension of the latch ring by which the latch ring is pivoted to the machine frame in the usual manner and so that the latch ring may be swung up and away from the needle circle when desired. The binder includes an automatically operated cutter 13 which severs the yarns or threads thrown out of action but does not

sever the high splice floats during each course of knitting which floats pass under the plate 14 of the binder as indicated by dotted lines, Fig. 1.

The mechanism with which this invention is particularly concerned consists of an arc-shaped plate or curved bar 15 carried by a bracket 16 connected to the latch ring as at 17. The plate 15 is, preferably, concentric with the circle of needles and is grooved as at 18 to receive a high splice float of the thread T as it is carried around by the last needle knitting the same into the fabric for a given course of the high splice. Such a needle is shown in a position 19, Figs. 1 and 5, the lever 4 at such time being in raised non-feeding position. As the needle in the position indicated by 19, Figs. 1 and 5, moves from such position around the needle circle, it carries a float of the thread T to the second position indicated by the numeral 20, Figs. 1 and 6, at which time the said thread is received within the groove 18 of the plate 15. Continued rotation of the needles carries the last high splice needle from the position indicated at 20 to a third position indicated at 21, Figs. 1 and 7, at which time the high splice float of the thread T, instead of passing from the first high splice needle shown at 22 straight across to the last high splice needle, as a chord, is deflected by the plate 15, the path of the float at such time being shown in full lines. Thereafter as the needle cylinder continues to rotate, the last high splice needle moves from the position shown at 21, Fig. 7, to the position shown at 23, Fig. 8, the first high splice needle in the meantime moving from the position shown at 22, Fig. 7, to the position indicated at 24, Fig. 8, in which position (Fig. 8) the float of the high splice thread T is shown as being between the float of the wrap thread W and the needle cylinder or in other words between the float of such wrap thread and the knitted fabric. Continued rotation of the needle cylinder finally carries the last high splice needle from the position shown at 23, Fig. 8, to a position indicated at 25, Fig. 9, the high splice float of the thread T then being confined between the short float of the wrap stripe thread W and the fabric, as clearly shown in said Fig. 9, the excess length of the high splice float of the thread T, due to the plate 15 drawing out considerably more thread for the high splice float than is necessary to span the diameter of the needle circle between the positions 21 and 22, providing slack in the high splice thread thereby permitting a plating thread W, which is fed to certain needles by an eye 10 and passes around the slack high splice float, to draw the latter against the rear face of the wales where the thread W is knitted into the fabric, the float of the plating thread extending in a substantially straight line from the last wale where it is knitted into the fabric in one course to

the first wale where it is knitted into the fabric in the following course as shown in Fig. 9.

Unless some means, such as hereinbefore described, is provided to act upon the high splice or other floats of thread T and permit the floats of the wrap stripe threads W to lie adjacent to the inner or rear face of the fabric, the high splice floats will extend in a substantially straight line across the needle circle and will cause the floats of the wrap thread W to be pulled out to a much greater length than is shown in Fig. 9, where it extends in a substantially straight line from the last needle which knits it into the fabric in one course to the first needle which knits it into the fabric in a following course.

In Figs. 5-9 inclusive a single course of high splice or double sole knitting has been illustrated diagrammatically; although in Fig. 9 there is shown, in broken lines, a wrap stripe thread passing through the eyelet 10 to the last needle around which the said thread was wrapped for the course of knitting following the course illustrated in Figs. 5-9 inclusive.

The usual needle cylinder is shown at 26 having mounted therein needles 27. Slidable radially within grooves in the sinker head 28 are sinkers 29 which sinkers are supported in their sliding movements by the sinker head and stitch ring 30.

Although high splice and double sole floats have been referred to it will be understood that whenever a reinforcing or other thread is knitted into the fabric for partial courses only, the means herein disclosed will act upon such thread and permit the floats of the wrap thread or threads to lie adjacent to the rear face of the fabric.

Throughout the specification and claims "threads" and "yarns" have been interchangeably used, although occasionally "yarns" has been used to designate the body yarns whereas "threads" has been used to describe the wrap threads; however, yarns and threads are synonymous.

Although the invention has been described in connection with a hosiery machine, it may be applied to so-called body machines or other machines for continuous circular work and is not necessarily limited in all respects to circle knitting machines nor to knitting machines having independent needles.

Claims:

1. A knitting machine including a rotary needle cylinder having needles mounted therein adapted independently to move to and from thread taking position, means for feeding a thread to all the needles and a second thread to certain of the needles only, the second mentioned thread floating across the partial courses, means for feeding a third thread to certain needles only and by needle wrapping movements of the said third

thread with respect to said last named certain needles, whereby the thread third mentioned encircles the mentioned floats of the thread second mentioned, and means so controlling the thread floats during knitting that such thread floats are drawn adjacent to the inner face of the fabric by the wrap threads.

2. A knitting machine including a rotary needle cylinder, needles mounted in the said cylinder and adapted to be moved independently to and from thread taking position, means for feeding a thread to all of the needles and an additional thread to certain of the needles only, the said additional thread being adapted to float from course to course substantially diametrically of the needle circle, means adapted to feed a third thread to certain of the needles only and by movements of the third thread around the last named certain needles, the wrapping floats resulting from the relative movements of the third thread with respect to the said certain needles enclosing the floats of the second mentioned thread, and means so controlling the thread floats during knitting that such thread floats are drawn adjacent to the inner face of the fabric by the wrap threads.

3. A knitting machine including a rotary needle cylinder, needles mounted in the said cylinder and adapted to be moved independently to and from thread taking position, means for feeding a thread to all of the needles and an additional thread to certain of the needles only, the said additional thread being adapted to float from course to course substantially diametrically of the needle circle, means adapted to feed a third thread to certain of the needles only and by movements of the third thread around the certain needles, the wrapping floats resulting from the relative movements of the third thread with respect to the said last named certain needles enclosing the floats of the second mentioned thread, and means adapted to act upon the second mentioned thread floats whereby the floats of the thread third mentioned will lie adjacent to the inner face of the fabric, the means last named consisting of an element adapted to engage the additional thread floats and increase the length thereof.

4. A latch ring for knitting machines, a thread feeding means carried thereby, a float thread engaging member associated with the said latch ring and positioned substantially diametrically opposite the thread feeding means and consisting of an arc shaped bar having a horizontally disposed thread receiving portion thereof substantially concentric with the latch ring.

5. A knitting machine including a rotary needle cylinder, needles mounted in the said cylinder and adapted to be moved in-

dependently to and from thread taking position, means for feeding a thread to all of the needles and an additional thread to certain of the needles only, the said additional thread being adapted to float from course to course substantially diametrically of the needle circle, means adapted to feed a third thread to certain of the needles only and by movements of the third thread around the certain needles, the wrapping floats resulting from the relative movements of the third thread with respect to the said certain needles enclosing the floats of the second mentioned thread, means adapted to act upon the second mentioned thread floats so that the floats of the thread third mentioned will extend in a substantially straight line from the last knit in wale of one course to the first knit in wale of another course, the means last mentioned consisting of an element adapted to engage the additional thread floats and increase the length thereof, and having a grooved, concentric thread receiving portion to receive and guide the first mentioned thread floats therein.

6. A latch ring for knitting machines, a thread feeding means carried thereby, a float thread engaging member also carried by the said latch ring and positioned substantially diametrically opposite the thread feeding means, and having a concentric thread receiving portion grooved to receive and guide the thread floats therein.

7. A latch ring for use in circular knitting machines, a thread or yarn binder carried thereby, the latch ring being provided with means for feeding threads or yarns to the needles and including thread or yarn to be knit in for partial courses only, the binder being provided with severing means adapted to sever any of the mentioned threads or yarns when withdrawn from feeding relation with respect to all of the needles, but not adapted to sever partial course floats of the thread or yarn knit in for partial courses, only, the said partial course floats normally floating as chords across the needle circle, means for wrapping one or more threads around selected needles, and means so controlling the thread floats during knitting that such thread floats are drawn adjacent to the inner face of the fabric by the wrap threads.

8. A latch ring for use in circular knitting machines, a thread or yarn binder carried thereby, the latch ring being provided with means for feeding threads or yarns to the needles and including thread or yarn to be knit in for partial courses only, the binder being provided with severing means adapted to sever any of the mentioned threads or yarns when withdrawn from feeding relation with respect to all of the needles, but not adapted to sever partial course floats of the thread or yarn knit in for partial courses

only, the said partial floats normally floating as chords across the needle circle, and means adapted to act upon the said partial course floats consisting of an element adapted to 5 increase the lengths thereof.

9. A circular knitting machine of the independent needle type provided with a rotatable needle cylinder, needles independently mounted therein, means for feeding threads 10 to the needles, one, at least, of said threads adapted to be knit in by certain of the needles only and float across the needle circle from the last knit in wale of one course to the first knit in wale of the following course, means 15 adapted to sever any one of the threads when withdrawn from feeding relation with respect to all of the needles, other means adapted to increase the length of the mentioned floats and positioned substantially opposite 20 the thread feeding means.

10. A latch ring for knitting machines, a thread feeding means carried thereby, a float thread engaging member positioned substantially diametrically opposite the thread 25 feeding means and consisting of an arc shaped bar having a grooved thread receiving portion thereof substantially concentric with the latch ring.

11. In a circular knitting machine of the 30 rotary cylinder type, needles and yarn guides for feeding a main yarn to all of the needles during the knitting of complete courses and an additional yarn to some of the needles for partial courses only, means for wrapping at least one thread around at least one of the needles during the knitting of the said partial courses, in combination with means for so controlling the said additional yarn during the knitting of said partial courses that 35 floats of the wrapping thread are permitted to extend along the inner face of the fabric and adjacent thereto, the additional yarn floats being confined between the thread floats and the inner face of the fabric.

45 12. A knitting machine including a rotary needle cylinder having needles mounted therein, means for feeding threads to the needles, one, at least, of such threads being adapted to be knitted into the fabric for partial courses only, means movable in time with the needle cylinder adapted to wrap at least one additional thread around at least one needle in such a way that floats of said additional thread would be elongated by a float 50 or floats of the thread knitted into the fabric for partial courses only, in combination with means adapted to act upon the thread last mentioned and in such a way that the floats of the wrap thread are permitted to lie adjacent to the rear face of the fabric.

55 13. In a circular knitting machine having rotary needles independently mounted therein, means for feeding a body thread to all of the needles and an additional thread to some 60 of the needles only, means for wrapping at

least one other additional thread around one or more needles, and means for so acting upon the first mentioned additional thread, which otherwise would elongate the floats of the wrap thread, as to permit the wrap thread 70 floats to lie adjacent to the inner face of the knitted fabric.

14. A circular knitting machine including a rotary needle cylinder having needles mounted therein, means for feeding at least 75 one thread to all of the needles and an additional thread to some only of the needles, other means movable in time with the needle cylinder for wrapping at least one other thread around selected needles, the said additional and wrap threads being presented to the needles in such a way that, unless avoided, floats of the said additional thread would be positioned between the rear face of the fabric and the wrap thread floats and 80 elongate the floats of such wrap thread, in combination with other means for so acting upon the said additional thread as to permit the floats of the wrap thread to lie adjacent to the rear face of the fabric.

15. A circular knitting machine of the rotary needle type having means for feeding at least one thread to all of the needles and a second thread to some only of the needles and a third thread to selected needles only in such 85 a way that, unless avoided, floats of the second thread would be positioned between the rear face of the fabric and the floats of the third thread and elongate the floats of such third thread, in combination with other 100 means for so acting upon the second thread as to permit the floats of the third thread to lie adjacent to the face of the fabric.

In testimony whereof I affix my signature.

ROBERT H. LAWSON.
